RAINPROOF VENTILATED MATERIAL

Karl Stich, Munich, Germany

Application April 4, 1951, Serial No. 219,161

2 Claims. (Cl. 2—87)

This invention relates to a novel type of rainproof ventilated material, particularly for waterproof clothing. Conventional ventilating means for waterproof clothing consist, for instance, of a plurality of transversely extending strips of material, which are overlapping each other and which are either of wave-like shape or provided with folds or the like. In other known ventilating contrivances of this type doubled-up strips of material or other distance regulating means of tubular or other suitable shape are arranged between two layers of fabric. However, ventilating contrivances of this kind are disliked by the public because of their unsightly appearance. And, in addition to that, the manufacture of such ventilating contrivances is complicated and requires much time and material, so that their production is rather expensive. It is further known to provide the waterproof garment or coat with ventilating means consisting of a plurality of transversely extending slits formed by a plurality of strips of fabric which are overlapping one another and which are secured to each other by means of adhesive substance or otherwise, either with or without the arrangement of distance regulating means between the strips. But a construction like that reduces the resistance to tearing of the material. Moreover, the slits do not guarantee a satisfactory ventilation of the coat, so that an undesired deposition of body humidity takes place on the inside of the garment.

Contrary to this the ventilating contrivance for rain-coats of waterproof material disclosed in the present invention is satisfactory in every respect and of simplest construction, as it does not require special ventilating means, such as little tubes, strips of material, spacing means and the like. The novelty resides in the feature that an inner and an outer layer of fabric are each provided with a plurality of arc-shaped incisions in such a way that the inner and outer arc-shaped incisions are curved in opposite directions and not positioned on top of each other, the two layers being fastened to each other only at the common intermediate portions. It is also possible to make the incisions provided in the inner layer of fabric of straight-lined formation. But best results will be obtained if the incisions in the inner layer are likewise arc-shaped and upwardly curved, whereas the arc-shaped incisions in the outer layer are downwardly curved. In a cheap and simple way like this ventilation channels or air passages can be produced which automatically open up and which afford a perfect protection against the penetration of water into the interior of the garment.

The invention will best be understood from a consideration of the following detailed description, taken in connection with the accompanying drawings, forming a part of this application and in which I have illustrated by way of example two embodiments of the invention. However, it is to be understood that the invention is not confined to any strict conformity with the showing of the drawings, but may be changed or modified, so long as such changes or modifications mark no material departure from the salient features of the invention as expressed in the appended claims.

In the drawings in which like parts are referred to by the same reference numerals in all of the several figures

Fig. 1 is a top-view of the outside of the ventilating contrivance with portions of the outer layer of fabric removed to show the oppositely curved incisions in the inner layer of fabric;

Fig. 2 is a vertical taken on line II—II of Fig. 1;

Fig. 3 is a vertical section on line II—II of Fig. 1 with the ventilating channels in opened-up condition through stretching of the two layers in upward and downward direction;

5 Fig. 4 is a detail view showing the inner layer provided with incisions of straight-line formation. Referring now to the drawings in detail, the ventilating contrivance consists of an outer layer or sheet of fabric 1 and an inner layer of fabric 2. As illustrated 10 in Figs. 1 and 2 the outer layer of fabric 1 is provided with arc-shaped incisions 4. These incisions have the tendency of opening up to some degree, even though the fabric may be lying on a support. When the garment made of the fabric is being worn, this opening-up tendency of the incisions is increased considerably by the weight of the fabric, so that the incisions will then assume the opened-up form illustrated in Fig. 3, in which the arc-shaped ends 3 of the fabric are protruding in flap-like or scale-like fashion. The inner layer of fabric 2 15 is likewise provided with incisions, which may be of the straight-lined and horizontally extending type as shown at 7 of Fig. 4, or of any other suitable form. It is preferable, however, to provide also the inner layer with incisions of arc-like shape, as illustrated in Figs. 1 to 3, in 20 which case the inwardly protruding arc-shaped ends or scales 5 will result. It will be seen that through the arrangement of the incisions in the outer as well as the inner layer a large number of air channels or passages 25 7 are produced, which extend from the outside of the garment to the interior of the latter, and which automatically open up when the garment is worn and thus guarantee a magnificent ventilation of the garment. The opposed surfaces of the layers of fabric 1 and 2 are 30 fastened to each other at the portions 6, positioned between the passages 7, through bonding, stitching, vulcanizing or welding. If the incisions 5 are provided in the inner layer of fabric 2 in reverse order as compared with the incisions 4 in the outer layer of fabric 1, as illustrated in Fig. 1, an entanglement of the incisions of the outer and inner layers is not possible. Because of 35 the peculiar way of the pairs of incisions are arranged, they will open up already to a certain extent when the fabric is spread out on a flat support, whereupon when the material is subjected to pull, even if the latter is 40 exerted only by the weight of the material, the passages will open up completely, as illustrated in Fig. 3, whereby a penetration of rain-water into the garment is absolutely impossible.

As the ventilating contrivance functions without pull 45 it is suited also for portions of the garment or coat at which no pull is exerted and at which, for that reason, a satisfactory ventilation has hitherto not been possible, for instance at the sleeves, particularly at the upper portion of the arm, in the vicinity of the seams, immediately below the places where the sleeves are attached to the garment, and around the waist portion of the latter. But it is also possible to provide the entire coat with 50 the ventilating means.

The manufacture of the ventilated material according 55 to the invention is simple and performed in the following way:

The arc-shaped incisions are punched in by machinery quickly and at low cost, whereby the same punching tool 60 may be used for both layers of fabric, as it is merely necessary to place the inner layer of fabric 2 under the tool in reversed order, as compared with the outer layer, before it is stitched or otherwise fastened to the outer layer 1. Long strips of material can be punched in continuous fashion, whereupon portions of fabric of the 65 size and shape needed for arrangement in the coat may be cut out. But it is also possible (and this is another advantage of the invention) to punch the incisions into the ready cut coat portions, so that the complicated fastening of the ventilating portions in the garment will not 70 be necessary. In this way unsightly seams will be avoided, which may endanger the waterproof condition of the coat and which, moreover, may reduce its resistance to tear. The resistance to tearing of the ventilating contrivance is greater than that of any other known 75 ventilating means, as it consists of two layers of fabric 1 and 2, which are firmly secured to each other, and as 80

the incisions in the two layers are curved in different directions, so that if at the ends of an incision of one layer of fabric tearing should occur it will normally not cause tearing of the appertaining but oppositely curved incision in the other layer of fabric. The incisions may be positioned either on top of one another or staggeredly arranged with respect to each other, as illustrated in the drawings. It is also possible to use more layers of fabric than two.

What I claim as new and desire to secure by Letters Patent of the United States is:

1. A rainproof ventilated material for a garment comprising two adjacent sheets having surfaces facing and contacting each other and being flatly interconnected, incisions in each of said sheets, said incisions extending substantially horizontally when the material is in actual use in the garment, the incisions in the outer one of said sheets in the garment being downwardly arcuated and the incisions in the inner one of said sheets in the garment being individually above the incisions in the outer sheet, the surface portions of said sheets between individual incisions in the outer sheet and individual

20

incisions in the inner sheet which are located individually above the incisions in the outer sheet to form individual pairs of incisions being interconnected for forming individual air channels between the incisions forming 5 pairs.

2. A material as specified in claim 1, in which the incisions in the inner one of said sheets in the garment are upwardly arcuated.
